(57) **CLAIM**

I claim the ornamental design for a utility towel, as shown and described.

DESCRIPTION

FIG. 1 is a front, bottom left perspective view of my design for a utility towel.

FIG. 2 is a front plan view thereof;

FIG. 3 is a rear plan view thereof;

FIG. 4 is a left side view thereof;

FIG. 5 is a right side view thereof;

FIG. 6 is a top side view thereof;

FIG. 7 is a bottom side view thereof; and,

FIG. 8 is a perspective view showing the utility towel in an alternate configuration of use.

The broken lines in the figures depict features of the utility towel that do not constitute a part of the claimed design.

1 Claim, 8 Drawing Sheets
